UNITED STATES PATENT OFFICE.

THOMAS D. KYLE, OF CHICAGO, AND EDWARD H. WAUGH, OF EVANSTON, ILLINOIS; SAID WAUGH ASSIGNOR TO SAID KYLE.

BOTTLE-HANDLING APPARATUS.

No. 851,425.

Specification of Letters Patent.

Patented April 23, 1907.

Application filed June 19, 1905. Serial No. 265,967.

To all whom it may concern:

Be it known that we, THOMAS D. KYLE and EDWARD H. WAUGH, both citizens of the United States, residing at Chicago, in the county of Cook and State of Illinois, and at Evanston, in the county of Cook and State of Illinois, respectively, have invented certain new and useful Improvements in Bottle-Handling Apparatus, of which the following is a specification.

Our invention relates to apparatus for handling bottles, more specifically being intended to co-operate in conjunction with bottle-washing machines in the way of supplying dirty or soiled bottles to the machine and removing the washed and cleansed bottles therefrom in an easy and expeditious manner.

The apparatus of our invention has been designed more especially for use in connection with bottle-washing machines of the general type and construction set forth in pending applications of David M. Kyle on bottle-washing machines, Serial No. 208,729, filed May 19, 1904, and Serial No. 230,584, filed October 29, 1904, said machines comprising essentially a rotary shaft containing a series of radially disposed bottle-holders or clamps rotating in a tank and provided with means for cleansing the interior of the bottles by washing fluid admitted through the shaft and the bottle-holding devices. The bottle-holders of such machines are arranged in comparatively wide radial groups or rows; and it is desirable to supply a complete row of bottles to the machine by a single operation, as well as to withdraw a complete row of cleansed bottles therefrom by a single operation, in order to expedite the charging and unloading of the bottle-washing machine. This latter is the primary purpose of the present invention, which consists essentially in a suitably mounted carrier adapted to reciprocate toward and from the periphery of the bottle-washing machine and provided with one or more angularly movable arms whereby soiled bottles may be taken from an overhead guide or chute and introduced to the machine, and the cleansed bottles may be withdrawn from the machine and discharged onto an underlying conveyor.

Our invention, in an approved mechanical form, is illustrated in the accompanying drawings, wherein,—

Figure 1 is a side elevational view, partly in vertical section, of our present apparatus, shown in connection with a rotary bottle-washing machine which appears in end elevation; and Fig. 2 is a front elevational view of the apparatus shown in Fig. 1.

Referring to the drawings, 5 may designate the bowl or tank of a rotary bottle-washing machine, on and above which is mounted a hollow shaft 6 containing a series of radially disposed bottle-holders or clamps indicated at 7, said shaft and bottle-holders being designed to rotate within the tank, carrying the bottles through the water therein and thus cleansing the exterior thereof, while water or suds admitted through the hollow central shaft 6 and holders 7 cleanses the interior of the bottles. The casing or tank 5 has an opening 8 on one side, which may or may not be closed by a suitable door, as desired. The foregoing description will suffice to explain the general nature of the bottle-washing machine with which our present invention is primarily designed to co-operate, although it is to be understood that the washing machine in itself forms no part of our present invention, being merely that on which the latter is designed to operate.

On the posts 9 opposite the open side of the washing machine tank is supported a pair of track rails 10 which, as shown in Fig. 2, may conveniently consist of a pair of angle iron bars preferably upwardly turned at their outer ends as shown at 10^a to form stops limiting the rearward travel of the bottle bearer or carriage.

11 designates the frame or truck of the carriage, which is mounted on suitable flanged wheels 12 that travel on the rails 10. The opposite side frame members of the carriage are rigidly connected and spaced by a rod 13 which serves the further function of a pivot rod for a pair of rigidly connected oscillatory bottle-carriers 14 and 15 arranged at an angle to each other, the former having the function of introducing the soiled bottles to the machine, and the latter having the function of withdrawing the cleansed bottles from the machine. The member 14 comprises essentially a broad flat plate having disposed across the upper surface thereof near its outer end a bar 16 provided with a series of bottle seats; while the member 15 is substan-

tially the same, being provided on its upper surface at its free end with a series of parallel beds 17 in which the bottles are designed to lie side by side. Extending rearwardly of 5 the pivoted shaft 13 are arms 18 fast with the members 14 and 15, which arms carry a series of counter-weights 19 designed to overbalance the members 14 and 15 when unloaded, and to permit the gentle descent of 10 the latter when loaded with bottles.

20 designates an overhead table or platform on which the soiled or dirty bottles 21 may be received; and 22 designates an inclined platform the upper surface whereof is 15 constituted by a series of parallel bottle chutes 23, the lower ends whereof are provided with openings 24 through which the bottles may drop. The lower margin of the platform 22 is provided with a foot board 25 20 extending both above and below the plane of the platform.

26 designates a rock shaft mounted in bearings 27 across the face of the platform 22 just above the openings 24. On this shaft is 25 mounted a channel-shaped escapement-bar 28 operated by an arm 29 fast on one end of the shaft 26.

Beneath and transversely of the inner ends 30 of the track rails 10 is mounted a suitable endless conveyor, indicated at 30.

In the operation of the machine, the soiled bottles are supplied to the table 20 upon which the attendant places them in endwise consecutive order in the chutes of the inclined platform 21, as shown in Fig. 1. The counter-weights 19 operate to maintain the bottle-transferring members 14 and 15 in the elevated position shown by full lines. The operator, rocking the arm 29, permits the 40 lowermost row of bottles in the chute to drop to and through the openings 24, whereupon said bottles are received upon the elevated end of the plate 14. The counter-weights 19 may be so adjusted that the bottles thus received will overbalance them, causing the plate 14 to descend to a horizontal position; or, said plate may be moved down by hand, whereupon, in either case, the carriage is moved inwardly toward the machine, carrying 45 the row of bottles into a position to be received by the holders or clamps of the machine, to which they are quickly connected. The carriage is then retracted, the counter-weights carrying the plate 14 again into the 50 elevated position, the escapement-bar 28 is again rocked, permitting the next row of bottles to descend and pass through the same operation, the shaft of the washing machine having been turned to a position to bring the 55 next radial row of members into favorable position to receive the bottles, etc. In this manner the machine is loaded with the soiled bottles. After the bottles have been washed, the apparatus may be employed to remove 60 the cleansed bottles by simply advancing the 65

carriage to the dotted line position shown, releasing the row of bottles immediately above the beds 17, retracting the carriage, and then tilting the carrier 15 to the downwardly inclined position to permit the bottles 70 to roll off onto the discharge conveyor 30, whereupon the counter-weights at once restore the carrier 15 to the horizontal position, and the above described operation may be repeated with the remaining rows of bottles. 75

From the foregoing it will be seen that our invention provides a simple and easily manipulated apparatus for handling bottles in quantities in the operations of introducing 80 them to and withdrawing them from a bottle-washing machine, such apparatus evidently saving much time and labor as compared with the purely manual operation of supplying and removing the bottles singly to 85 the clamps or holders.

We claim:

1. In a machine for the purpose described, the combination with a carriage, of a bottle carrier mounted thereon adapted to receive 90 soiled bottles and deliver them to the bottle holders of a bottle-washing machine, and another bottle carrier mounted on said carriage adapted to receive cleansed bottles from said bottle holders and deliver them at a suitable 95 point of discharge, substantially as described.

2. In a machine for the purpose described, the combination with a delivery chute, of a carriage, and a bottle carrier mounted on said carriage movable relatively thereto and 100 adapted to receive soiled bottles from said chute and deliver them to the bottle holders of a bottle-washing machine, substantially as described.

3. In a machine for the purpose described, 105 the combination with a discharge conveyor, of a carriage, and a bottle carrier mounted thereon movable relatively thereto and adapted to receive cleansed bottles from a bottle-washing machine and deliver them to 110 said conveyor, substantially as described.

4. In a machine for the purpose described, the combination with a delivery chute, of a carriage, and a counter-weighted bottle carrier pivotally mounted on said carriage adapted to receive soiled bottles from said chute and deliver them to the bottle holders of a bottle-washing machine, substantially as described. 115

5. In a machine for the purpose described, 120 the combination with a discharge conveyor, of a carriage, and a counter-weighted bottle carrier pivotally mounted on said carriage adapted to receive cleansed bottles from a bottle-washing machine and deliver them to 125 said conveyor, substantially as described.

6. In a machine for the purpose described, the combination with a delivery chute and a discharge conveyor, of a carriage, and a pair 130 of counter-weighted bottle carriers pivotally

mounted on said carriage and disposed at an angle to each other, one of said carriers being adapted to transfer soiled bottles from said chute to a bottle-washing machine, and the 5 other to transfer the cleansed bottles from said washing machine to said conveyor, substantially as described.

7. In a machine for the purpose described, the combination with a carriage, and a bottle 10 carrier mounted thereon having seats for a row of bottles, of a chute adapted to feed bottles in successive rows to said carrier, and an escapement device on said chute controlling the delivery of said rows of bottles, substantially 15 as described.

8. In a machine for the purpose described, the combination with a track and a carriage reciprocable thereon, of a counter-weighted bottle carrier pivotally mounted thereon, a chute adapted to feed the bottles in successive rows to said carrier, and an escapement device on said chute controlling the delivery of said rows of bottles, substantially as described. 20
